UNITED STATES PATENT OFFICE.

CHARLES J. CARLSON AND OSCAR M. ELTON, OF HELENA, MONTANA.

STEAM BOILER.

Application filed April 23, 1923. Serial No. 634,062.

Our invention relates generally to steam boilers, more particularly to boilers of the semi-flash type of construction and it consists in the combinations, constructions and arrangements herein described and claimed.

An object of our invention is to provide a boiler of the character described having means for feeding water to a pre-heating coil comprised in the device in such manner that the quantity of water fed to the pre-heating coil varies directly with the quantity of water discharged from the pre-heating coil and vaporized in the boiler, whereby flooding of the steam chamber of the boiler at any time is precluded and the feeding at all times of a quantity of water to the boiler sufficient to effect the efficient operation of the latter is insured.

A further object of the invention is to provide a boiler of the character described which has facilities for vaporizing a given quantity of liquid in a relatively short time and for utilizing to a relatively great extent the heat resulting from the combustion of a given quantity of fuel, whereby an economy is effected in the production of a given amount of power.

A still further object of the invention is to improve the construction of boilers of the type described in such manner as to insure the equalization of steam pressure within all parts of the device which are accessible to steam from the boiler.

A still further object of the invention is to provide in a boiler of the character described a novel means for feeding water to the vaporizer element of the device.

Other objects and advantages will be apparent from the following description, considered in conjunction with the accompanying drawings, in which

Figure 1 is a side elevation of a boiler embodying the invention, a portion of a tank appurtenant thereto being broken away,

Figure 2 is a fragmentary plan view showing a portion of the structure exhibited in Figure 1.

Figure 3 is a view mainly in vertical section and partly in side elevation, showing the structure exhibited in Figure 1,

Figure 4 is a relatively enlarged vertical section through a valve and associated parts

included in the structure exhibited in Figures 1 and 2,

Figure 5 is a vertical section substantially along the line 5—5 of Figure 4,

Figure 6 is a vertical central section through a second valve comprised in the device, being an enlarged view substantially along the line 6—6 of Figure 3,

Figure 7 is a horizontal section through the valve shown in Figure 6,

Figure 8 is a longitudinal central section through a discharge head for a preheating coil comprised in the device and through the connection of the discharge head with the preheating coil,

Figure 9 is a plan view of the discharge head,

Figure 10 is a top plan view of an automatic valve which is adapted to be substituted for certain of the parts shown in Figures 1 and 2, a portion of the casing of the valve being broken away, and

Figure 11 is a longitudinal central section through the automatic valve.

Referring now to the drawings and particularly to Figure 3 thereof, it will be noted that the casing of a boiler embodying the invention comprises substantially concentric inner and outer shells 1 and 2 respectively spaced apart and connected at their lower ends by a horizontally disposed annular plate 3 which rests upon the open upper end of a hollow base 4. The chamber within the hollow base 4 constitutes an ash pit and the annular plate 3 receives a frame 5 which is disposed above the ash pit and supports a series of grate bars 6 which preferably are mounted in any suitable known manner so that they can be rocked through the agency of a lever 7 which is fulcrumed on the outer wall of the base 4 and is connected by any suitable known means (not fully shown) to the grate bars.

The outer shell 2 is provided with a central opening in its upper end receiving an annular flange 8 on a jacket 9 which is provided for the inner shell 1 and which protrudes through the opening in the upper end of the outer shell above the level of the latter, the upper end portion of the jacket being removable and attached to the body thereof by bolts 10 or like fastening elements.

With the arrangement described, the space within the inner shell 1 constitutes a combustion chamber which is provided with a fuel feed opening normally closed by a door 11 and with a clean-out opening normally closed by a door 12. The door 11 is apertured, the apertures therein being controlled by a draft regulating closure 13 of any suitable known construction.

10. The hollow base 4 also is provided with an opening normally closed by a door 14 having the usual draft opening formed therein and controlled by a door 15. The combustion chamber communicates adjacent 15 to its upper end through ports 16 with the space between the jacket 9 and the outer shell 2, which latter space constitutes a heating chamber into which the heated products of combustion pass from the combustion chamber. An annular baffle 17 depends from the inner wall of the outer shell 2 in spaced concentric relation to both the outer shell and the jacket. The annular baffle 17 terminates at its lower end at a considerable 20 distance below the level of the ports 16 and above the level of the horizontal plate 3, whereby the heated products of combustion passing through the ports 16 into the heating chamber are compelled to pass downwardly close to the jacket 9 to the lower end of the baffle 17 and then can pass upwardly between the latter and the outer shell 2 to an outlet 18 which is provided for the heating chamber adjacent to the upper end of the latter and which extends outwardly 25 from the outer shell for connection with any suitable means, not shown, for conducting the heated products of combustion to a desired place. The outlet 18 is provided with the usual lateral draft opening controlled by a door 19.

The space within the jacket 9 and between the latter and the inner shell 1 constitutes a combined water leg and steam chamber 45 into the upper part of which water is discharged from a discharge head 20 which is connected by a conduit 21 extending through an axial opening in the inner shell with the upper ends of concentric coils 22 and 23 respectively which are disposed in the upper part of the combustion chamber. As illustrated to advantage in Figures 8 and 9, the discharge head 20 comprises a horizontally disposed circular plate 24 having the outer edge portion thereof turned upwardly to provide an upwardly inclined marginal flange 25 which has a series of spaced apart vertical notches 26 extending in the flange 25 from the outer edge thereof to the plane 50 of the upper face of the plate 24. The plate 24 has a central opening 27 receiving the upper end of the conduit 21 which preferably terminates at its upper end flush with the upper face of the plate. A deflector cap 55 overlying the opening 27 comprises a down-

wardly dished substantially circular body 28 supported in horizontal position at its outer edge by a plurality of spaced apart relatively narrow vertical lugs 29 having horizontal attaching portions 30 at their lower ends resting upon and secured to the plate 24, the portion of the body 28 which is indicated at 31 and which is in axial alignment with the opening 27 being slightly raised or bulged upwardly. The arrangement is such that 70 a stream of water discharged from the conduit 21 will strike the deflector body 28 and will be deflected downwardly and outwardly against the upper face of the plate 24 and outwardly in a thin sheet on the latter 75 against the flange 25 by which it will be broken up because of the provision of the vertical notches 26 through which it will pass in a finely divided condition and fall by gravity upon the heated outer side of 80 the inner shell 1.

Since the supply of water has been broken up in the manner described and of course has been pre-heated during its passage through the coils 22 and 23, the greater part 85 of the water passing from the discharge or spreader head 20 into contact with the heated inner shell 1 will be vaporized and the resultant steam will pass upwardly and outwardly from the upper part of the combined 90 steam and water chamber through a steam delivery conduit 31'. A steam gauge 32 of conventional construction may be provided and operatively connected with the upper part of the combined water leg and 95 steam chamber.

The water not converted into steam in the upper part of the combined steam chamber and water leg will fall by gravity in the latter in contiguous relation to the wall of the heated inner shell 1 and will strike annular ribs 33 which are arranged in a vertical series on the outer wall of the lower portion of the inner shell 1 in encircling relation to the latter, the respective ribs 100 33 being spaced apart and upwardly inclined. The water striking the ribs 33 will be broken up and part thereof will be retained between the inclined upper faces of the ribs and the outer wall of the inner shell 110 1 and thus quickly vaporized. The ribs 33 also aid in effecting a relatively great radiation of heat from the combustion chamber outwardly into the combined steam chamber and water leg.

The water which falls into the lower end of the combined water leg and steam chamber without being vaporized collects in the lower part of the latter as indicated at 115 34, the combined water leg and steam chamber being in open communication adjacent to its lower end through a nipple 35 with the lower end of a coil 36 which is disposed in the lower part of the combustion chamber, the other end of the coil 36 being in open com- 120 125 130

munication with the combined water leg and steam chamber at a higher level through a nipple 37. The combined water leg and steam chamber also communicates adjacent to its lower end through a horizontal exhaust conduit 38 with a vertical float chamber 39 at a point intermediate the length of the latter. The float chamber 39 may be provided with a gauge glass 40 and may have a drain opening in its lower end controlled by a cock 41. A float 42 disposed within the chamber 39 is connected to the lower end of a vertical valve stem 43 which is connected at its upper end by a ball and socket joint 44 (see Fig. 7) with the lower end of a valve 45 which is slidably received within a vertical valve casing 46 in open communication at its lower end through a tubular housing 47 with the upper end of the float chamber. A manually operable valve 48 may be provided in the conduit 38.

The valve casing 46 is provided with a lateral inlet 49 with which a supply conduit 50 leading from the lower part of a tank 51 is connected. The valve casing 46 also is provided with a lateral outlet 52 at the same level as the inlet 49 and connected by a horizontal conduit 53 extending through the outer shell 2, baffle 17 and the jacket and inner shell 1 into the combustion chamber, being connected at its inner end by a suitable pipe connection 54 to the lower end of the coils 22 and 23. The valve 45 has an annular groove 55 in its outer periphery which establishes communication between the inlet 49 and the outlet 52, the volume of water permitted to pass from the inlet to the outlet being determined by the position of the valve 45 in the casing 46 but the arrangement being such that the valve 45 cannot be moved to such position in the valve casing that the annular groove 55 will be entirely out of communication with the inlet and outlet. The conduit 50 may be provided with a valve 56 and with a drain cock 57.

Water may be supplied to the tank 51 through a conduit 58 which communicates with the upper part of the tank and which may be connected with any suitable source of water supply. The tank 51 may be provided with a gauge tube 59 and is supported upon brackets 60 carried by the outer shell 2 so that the tank extends both above and below the level of the water discharge head 20. For the purpose of overcoming steam pressure from the boiler in the event that the pressure at which the water is forced through the conduit 58 into the tank 51 is not sufficient and in order to control the supply of water to the tank, a valve 61 may be incorporated in the conduit 58. The valve 61 is best seen in Figures 4 and 5 and comprises a valve casing 62 having diametrically opposite vertically aligned inlet and outlet ports 63 and 64 respectively with

which axially aligned sections of the conduit 58 communicate, the inlet being uppermost. A hollow valve body 65 interfits the casing 62 and is mounted to rotate about a horizontal axis, being provided with oppositely extending axially aligned horizontal trunnions or journal pins 66 and 67 respectively, the former being rotatably received within a closed bearing 68 provided on the valve casing and the latter being of sufficient length to extend through a lateral, tubular bearing 69 and a stuffing box 70 carried thereby outwardly from the stuffing box. A pulley 71 is secured on the extending end portion of the trunnion 67 and is driven by a belt 72 suitably connected with the drive shaft of a motor 73. When the motor is operated the valve body 65 will be rotated continuously. The hollow valve body has a plurality of ports 74 through its walls arranged in a circumferential series and each adapted to register in turn with the inlet 63 and the outlet 64 during one complete rotation of the valve body. Each port 74 is spaced less than 180° from the adjacent port 74 so that the outlet 64 will be out of communication with the interior of the hollow valve body when one of the ports 74 is in register with the inlet and likewise the inlet 63 will be out of communication with the interior of the valve body when one of the ports 74 is in register with the outlet. With this arrangement, water will pass by gravity from the upper section of the conduit 58 through the inlet 63 and one of the ports 74 completely or partially filling the latter before the hollow valve has been rotated to an extent sufficient to position one of the ports 74 in register with the outlet 64. When in the latter position, the contents of the hollow valve body will pass by gravity to the lower section of the conduit 58 into the tank 51. The motor 72 may be operated in any suitable known manner, preferably being an electric motor provided with a motor operating circuit. The motor operating circuit is controlled by a switch indicated at 75 and shown more or less diagrammatically in Figure 1, the switch being controlled by a float 76 disposed within the tank 51 and arranged when the level of the liquid in the latter has risen to the level of the water discharge head 20 to operate the switch and open the motor operating circuit so that the supply of water fed to the tank will be discontinued. When the level of the water within the tank 51 has fallen below that of the discharge head 20 the switch will be operated to close the motor operating circuit, resulting in water again being fed to the tank.

The condensate resulting when the steam delivered to the pipe 31' has been reconverted into liquid may be returned to the combined water leg and steam chamber by

means which will now be described. Such means may comprise a condensate supply tube 77 leading from any desirable place to a trap 78 having a lateral outlet 79 above the level of the lower end thereof, the lateral outlet 79 communicating with a pipe 80 which opens into the combined water leg and steam chamber at a point adjacent to the lower end of the latter. Steam entrained 10 with the condensate will collect in the trap 78 and pass therefrom through the conduit 80 to the combined water leg and steam dome. The condensate will pass from the lower end of the trap or catch basin 78 15 through a vertical conduit 81 which communicates at its lower end with the water supply conduit 53 and the condensate thus will be returned to the coils 22 and 23. A valve 82 for controlling the flow of condensate through the conduit 81 is adapted 20 to be operated by a laterally extending valve operating arm 83 carrying a weight 84 at its outer end and connected pivotally intermediate its length with the upper end of a 25 vertical piston rod 85 extending from a piston 86 slidably disposed within a vertical casing 87. A steam pipe 88 which may be controlled by a manually operable valve 89 extends from the upper part of the combined 30 water leg and steam chamber to the lower part of the cylinder 87, being in open communication with both the combined water leg and steam chamber and the cylinder. When the boiler is in operation, steam will 35 pass through the pipe 88 into the cylinder 87 below the piston and will raise the latter to effect such movement of the valve operating arm 83 as will maintain the valve 82 in open position. Steam is exhausted from cylinder 87 through an exhaust conduit 90 which has a branch 91 communicating with the tank 51 and which communicates at its lower end with the upper end of the valve casing 46, as clearly shown in Figures 3 40 and 6. The steam pressure within all parts of the water circulatory system described in the foregoing will thus be equalized and therefore there will be no restriction of flow of water through such circulatory system. 45 When the boiler is not in operation, the piston 86 will fall by gravity in the cylinder 87 to an extent sufficient to cause closing of the valve 82.

In lieu of the cylinder 87, the valve 82 and the parts hereinbefore described as being associated with the cylinder and valve, we may provide an automatic valve such as that illustrated in Figures 10 and 11. In the construction shown therein, a vertical valve casing 92 is formed with a lateral inlet 93 intermediate its length and adapted for connection with a section of the conduit 81, the casing 92 also being provided with a lateral outlet 94 at the same height or level as the inlet and adapted for connection with the

lower section of the conduit 81. A piston valve 95 has an annular groove 96 in its periphery and is pressed downwardly within the casing 92 by an expansion spring 97 arranged about the piston stem 98 between the head of the casing and the piston valve so that the groove 96 is normally out of register with the inlet and outlet. The casing 92 also has an inlet 99 at its lower end adapted for connection with a steam supply pipe 88 and an outlet 100 also at its lower end adapted for connection with a steam exhaust pipe 90. When the boiler is in operation, steam will enter the casing 92 and force the piston valve 95 upwardly until the groove 96 is in position to establish communication between the inlet 93 and the outlet 94. The stem 98 carried by the piston valve 95 protrudes from the upper end of the casing and by its position indicates the position of the piston valve 95 in respect to the level of the inlet 93 and outlet 94.

The outer shell 2 may be provided with soot clean out openings normally closed by doors or cover plates such as indicated at 101 and 102.

From the foregoing description of the various parts of the device, the operation thereof will be readily understood. It will be apparent that the means described in the foregoing for feeding water to the preheating coils will preclude the flooding of the steam chamber for any cause, as for instance insufficient heat within the combustion chamber for the efficient operation of the device, since the quantity of water fed to the heating coils will increase as the ratio of steam to the unvaporized water resulting when a given quantity of water is fed to the preheating coil increases. At the same time, the minimum quantity of water which will be fed to the preheating coils will be sufficient to effect operation of the boiler to full capacity and to maintain sufficient water in the water leg around the combustion chamber for the protection of the latter. An economy in the use of water and also in the use of fuel to provide a given amount of power will be effected when our improved boiler is used.

The exhaust steam entering the upper part of the valve casing 46 through the conduit 90 is permitted to pass through an axial bore 103 and the branches 104 of the latter to the lower part of the valve casing 46 and thence through the tubular housing 47 to the float chamber 39. The bore 103 also is provided with lateral ports as indicated at 105. The steam pressure on the water within all parts of the water conducting system hereinbefore described is thus equalized.

Obviously, our invention is susceptible of embodiment in forms other than that illustrated in the accompanying drawings and we therefore consider as our own all modifications and adaptations of the form of the

device herein described and claimed which fairly fall within the scope of the appended claims.

Having thus described the invention, what we claim is:—

1. In a boiler, a casing formed to provide a combustion chamber and a steam and liquid compartment adjacent thereto, a water conducting coil disposed within said combustion chamber and arranged to discharge into the steam and water compartment, means connecting with the water conducting coil for conducting water from a source of supply to said coil, a valve controlling said water supply means, a float chamber extending slightly above the level of the lower end of said steam and water compartment, a conduit lying at the level of the lower end of said steam and water compartment and connecting the latter with said float chamber, a float in said float chamber and adapted to rise and fall with the water in the latter, and means connecting the float and said valve, whereby the latter will be actuated in response to the rise and fall of the float within the float chamber.
2. In a boiler, a casing comprising spaced substantially concentric inner and outer shells, an imperforate annular ring connecting the lower ends of said inner and outer shells, and a jacket encompassing the inner shell in spaced relation thereto, said outer shell having a central opening in its upper end through which the upper end portion of said jacket extends, said casing being formed to provide a port extending through said inner shell and said jacket adjacent to the upper end of the former, said port communicating with the upper part of the space within said outer shell, and a continuous baffle concentric with said inner and outer shells and depending from the inner wall of the outer shell from a plane above the level of said port to a plane considerably below the level of the port, as and for the purpose described.

CHARLES J. CARLSON.
OSCAR M. ELTON.
